UNITED STATES PATENT OFFICE.

ARMAND HECTOR DUVAL, OF WALTHAM, MASSACHUSETTS.

LOOM FEELER.

Application filed November 8, 1922. Serial No. 599,707.

To all whom it may concern:

Be it known that I, ARMAND HECTOR DUVAL, a citizen of the United States, residing at Waltham, in the county of Middlesex 5 and State of Massachusetts, have invented certain new and useful Improvements in Loom Feelers, of which the following is a specification.

This invention relates to bobbin feeler 10 mechanism for looms wherein it is desired to reduce the waste on the running bobbin to the minimum.

It is an object of the invention to produce a feeler of this class that is simple, efficient, and cheap to manufacture, and which is composed of very few parts.

A further object of the invention is to so simplify the structure of the feeler, that feeler brackets already in existence may 20 be rapidly equipped therewith at but slight expense and very little loss of time.

Another object of the invention is to produce a feeler of this class having a bobbin contact member which is normally out 25 of but, tending to assume bobbin transferring position, but which is restrained therefrom until contact actually takes place and the contact member has been moved forwardly.

It is not known that a feeler has ever 30 been used wherein the bobbin contact member is normally held out of bobbin transferring position, but which is always under the influence of an actuator; such as a 35 spring, to immediately move it into such position at the proper time and which is normally held out of bobbin transferring position by a device which causes said member to be reset after each bobbin transfer.

Nor is it known that a feeler has ever 40 been used having as small a number of parts which can be attached to existing devices such as the feeler bracket and slide.

The invention further consists in certain 45 novel features of construction and arrangement of parts which will be fully understood from a description of the drawings and the claims hereinafter given.

Of the drawings: Figure 1 represents 50 in top plan view a sufficient portion of a loom with the invention applied thereto to enable it to be understood.

Figure 2 an enlarged top plan view of

the feeder shown in contact with a full 55 bobbin.

Figure 3 a side elevation of the feeler shown in Figure 2.

Figure 4 a partial view of the feeler as shown in Figure 2 but showing the position it would assume when in contact with a 60 nearly spent bobbin and about to cause bobbin transfer.

Like characters represent like parts 65 throughout the several figures of the drawings.

Referring to the drawings: The drawings herewith show the invention as applied to the well known Northrop loom wherein the battery 10 is provided with a plurality of full bobbins 11 awaiting their turn to 70 be transferred to the shuttle 12.

The transfer of a bobbin may be initiated by a filling feeler which in some instances is set to eject a bobbin, and supply a full one just before complete exhaustion of the 75 ejected bobbin.

The present invention contemplates a filling feeler of such construction that a bobbin transfer is not effected by the feeler until a portion at least of the running bobbin has been exhausted to such extent that the barrel thereof is met by the feeler contact member. 80

It will also be understood that it is intended to cause bobbin transfer just before complete exhaustion of the running bobbin transfer as provision is made to bare the said barrel at the feeler contact point and cause the transfer while there is still a sufficient quantity of yarn on the bobbin to 90 complete at least one pick of the shuttle. 85

At the left side of the loom and fast to the lock plate 13 is a feeler carrying bracket of box-like structure 14 and of a design well known in the art. 95

Mounted in said bracket 14 is the usual slide member 15 which is normally held in the position shown in Figures 1 and 2 by the spring 16.

Pivotedly mounted to the said slide is a 100 bobbin contact member 17 upon which the tension of the spring 18 is always exerted, tending to move said member into the position shown in Figure 4.

In the normal position of the feeler, 105 however, the said member 17 is prevented

from assuming the said position by a combined stop and resetting plate 19 which is adjustably secured to the feeler bracket 14 by one of the usual or existing bracket 5 screws 20.

The member 17 at the bobbin end may be provided with a toothed contact surface 21 for a purpose to be described and at its other end having an upstanding portion 22 adapted to abut the inclined edge 23 of the stop plate 19, which normally prevents the member from being swung to the position seen in Figure 4.

Slidably mounted in a suitable guide 24 of the bracket 14 is an intermediate member 25 which is adapted to be met and actuated by the portion 22 at a certain time, and which in turn may actuate a pivoted spring pressed lever 26 normally held in 20 the position shown in Figure 1.

The lever 26 in turn coacts with a cam surface, not shown, of a pivoted lever 27 the end 28 of which is adapted to be depressed upon feeler actuation, to lower the lever 29 or the end thereof into the path of a regularly moving part of the loom such as a dog 30 carried by the weft hammer 31.

In this instance the lever 29 is pivoted 30 to a lever 32 and rests upon the end 28 of the lever 27, the said lever 32 being fast upon the starting shaft 33, a partial rotation of which, as is well known, causes the 35 transferring means of the battery to be positioned for actuation.

As the invention does not include the devices which are intermediate the feeler and the battery or magazine, it is obvious that 40 any suitable combination of devices may be used which may derive their movement from the feeler.

In order to permit the bobbin contact member 17 of the feeler to be engaged by the running bobbin B, the shuttle box wall 45 35 and shuttle wall are provided with entrance slots 36, and 37, respectively.

During the regular running of the loom with a full bobbin in the shuttle, on each forward beat of the lay when the shuttle 50 is in the left hand box, the feeler will enter the slots 36 and 37 and the member 17 will meet the yarn of the bobbin and the teeth 21 will sink into it.

The lay will continue its forward movement 55 forcing the slide 15, through its connection with the said member 17, against the spring 16, and the portion 22 will be caused to travel forwardly while maintaining its relative position with the slide shown 60 in Figure 2.

At this time and in fact at all times the spring 18 is exerting its power to swing the member 17 into the position shown in Figure 4, but as before stated the teeth 21 are now engaged with the yarn on the bobbin 65 on the beat up of the lay and prevent the swinging movement.

If, however, the yarn on the bobbin has been exhausted to a point wherein the bare barrel of the bobbin is exposed as shown in 70 Figure 4, the teeth will then find nothing to grip and the spring will exert its power, and as the slide 15 is forced forwardly the portion 22 instead of moving in a straight line as before, will be gradually swung toward the member 25, or as rapidly as the speed of the lay and the incline 23 permits, until it is in position to strike said member 25 forcing it forward, and through the devices previously explained cause a bobbin 80 transfer.

When the transfer has been completed and the lay moves rearwardly the slide 15 will follow it to the extent of its own movement, under the action of the spring 16, and in so doing the portion 22 will be caused to travel along the incline 23 toward the free end thereof which action resets the feeler member 17 to its normal position, as seen in Figures 1 and 2.

Having described the invention I claim:

A loom feeler of the class described, comprising existing elements such as a feeler bracket and a feeler carrier slide mounted in said bracket and normally under the control of a spring in said bracket, all as used on existing looms, in combination with a bobbin contact member pivoted midway of its length on said carrier slide and having its rear end extending beyond it, and its forward end upwardly turned to engage a cam plate; a spring on said slide normally holding said contact member and said plate in engagement; a cam plate adjustably secured to said bracket by an existing screw, said plate projecting rearwardly and laterally to overlie said slide and forward portion of said contact member and providing a cam surface to co-operate with the upwardly turned end of said contact to normally retain said member in bobbin feeling position and to reset said member after bobbin transfer; a second slide member overlying said carrier slide mounted in an existing guide way of said bracket and adapted to be actuated by the upturned end of said contact member; and means coacting with said second slide member to effect bobbin transfer.

ARMAND HECTOR DUVAL.
